REFLECTIVE RAT TRAP PEDAL

Carlton P. Pawsat and Robert F. Humlong, Maysville, Ky., assignors to Wald Manufacturing Company, Inc.

Continuation-in-part of abandoned design application Ser. No. 320,471, Jan. 2, 1973. This application May 20, 1974, Ser. No. 471,518

Term of patent 14 years

Int. Cl. D12—11

U.S. Cl. D12—125

FIG-1

FIG-2

FIG-3

FIG-4

FIG-5

FIG-6

FIG-7

FIG-8

FIG. 1 is a top perspective view of one end of a reflective rat trap pedal showing our new design.

FIG. 2 is a bottom perspective view of the opposite end thereof.

FIG. 3 is a side elevational view thereof.

FIG. 4 is an elevational view of the left end of FIG. 1.

FIG. 5 is an elevational view of the left end of FIG. 2.

FIG. 6 is a top perspective view of one end of a reflective rat trap pedal showing a second embodiment of our new design.

FIG. 7 is a bottom perspective view of the opposite end of the embodiment shown in FIG. 6.

FIG. 8 is a side elevational view of the embodiment shown in FIG. 6.

This application is a continuation-in-part of co-pending application, Ser. No. 320,471, filed on Jan. 2, 1973, and now abandoned.

We claim:

The ornamental design for a reflective rat trap pedal, as shown and described.
